HERMAN SCHLAICH, OF LONG ISLAND CITY, NEW YORK.

SPARK PLUG.

Application filed April 30, 1927. Serial No. 187,979.

This invention relates to spark plugs for internal combustion engines and the invention has for its principal object the provision of a spark plug having a variable spark gap so constructed as to provide for the production of an intense ignition spark under all operating conditions.

In spark plugs as now in general use a spark gap of fixed width is provided within the motor cylinder across which the spark is caused to jump. This gap has necessarily been limited to a width which the spark can readily jump when conditions are most unfavorable to its passage. Such conditions occur when the motor is cold and particularly at starting. If the ignition potential is furnished by a magneto such potential will be at its minimum value when starting the motor due to the slow rotation thereof, while if the ignition current is furnished by the storage battery which furnishes the power for the electric starter, the starter draws on the battery so heavily as to momentarily greatly reduce its voltage, thereby reducing the ignition potential proportionately. Furthermore, the resistance of the spark gap is greater in a cold motor owing to the absence of hot gases and to the incomplete vaporization of the fuel. All of these conditions unite to require the use of a comparatively narrow spark gap, if the motor is to start properly.

On the other hand, it has been found that as the motor warms up, a substantially wider gap produces better ignition. This is partly due to the fact that as wide a gap as it is possible for the spark to jump with regularity is in all cases desirable, and the increased potential available under running conditions permits the use of such wider gap; and because it has been found that as the motor warms up the intensity of the spark across a gap of fixed width noticeably diminishes due to diminished resistance of the gap, caused in part by the rise in temperature of the gases in the gap, and the increased temperature of the electrodes.

If a narrow spark gap is used there is moreover danger of short circuiting, due to fouling of the plug which may result from a particle of carbon becoming lodged between the firing points so as to bridge the gap and prevent the production of a proper spark.

As a result of the conditions named, the spark gaps used in the ordinary fixed point spark plugs constitute a compromise between

the narrow gap most desirable for starting and the wider gap most desirable for normal running. The gap is usually neither narrow enough to make the motor start easily, nor wide enough to produce the best ignition when running.

In accordance with the present invention a variable spark gap is provided which is controlled automatically by temperature conditions within the cylinder, so that it is narrow at starting when the motor is cold, and is widened when the motor heats up, to a width which would be too great for easy starting with a cold motor, but which gives the best results under operating conditions. At the same time the present invention provides a construction for accomplishing this result which is mechanically simple and efficient, compact, and of such nature as to provide for the proper conduction away of the heat from the elements of the device so that none of such elements tends to become overheated to a point where preignition may occur.

A further feature of the invention relates to the distortion characteristic of the thermostatic element employed, it being a feature that a combination of metallic strips for the thermostatic element is contrived such that distortion of the element occurs up to a predetermined point, below the normal maximum operating temperature, and that, due to a change in the relative co-efficients of expansion, there is no further distortion of the element above such point. Thus the thermostatic element causes the spark plug gap to increase to its maximum width below the temperature at which the vehicle motor normally operates when warmed up and subjects the element to no further distorting strain when high temperatures are reached at which the metals of the element may be permanently distorted if subjected to strain. This feature is important because it assures the return of the gap to its original minimum width when it is again cooled, and also because it causes the maximum width of the spark gap to be limited automatically.

The present application is a continuation in part of my application Serial No. 103,200, filed April 20, 1926 for spark plugs and spark intensifiers.

Other objects and advantages of the invention will appear from the following description of a preferred embodiment thereof.

In the drawings forming a part of this

specification in which such preferred embodiment is illustrated:

Figure 1 is an elevation of a spark plug embodying the improvements of the present 5 invention;

Figure 2 is a bottom plan view of the spark plug shown in Figure 1;

Figure 3 is a fragmentary vertical sectional view of the lower part of the plug;

10 Figure 3^a is a fragmentary elevation showing the same parts of the spark plug shown in Figure 3;

Figure 4 is a plan view of a thickness gauge preferably forming a part of the plug;

15 Figure 5 is a fragmentary, vertical section of the lower end of a modified embodiment of the spark plug;

Figure 6 is a bottom plan view of the spark plug of Figure 5; and

20 Figure 7 is a fragmentary, enlarged, sectional view illustrating a detail of the connection of the bi-metallic element of Figures 5 and 6 to the spark plug shell.

The present invention is applicable to various 25 constructions of plugs, the particular plug illustrated comprising the conventional externally threaded metallic shell 1, for secure-
ment in the cylinder casting, an insulator 2 of porcelain or other suitable material, a nut 30 3 clamping the insulator in the shell 1, and a fixed, central electrode 4 carried by the porcelain. Provision is made of a terminal binding nut 5 at the outer end of the spark plug for securing a wire of the ignition system 35 in conductive relation with the central electrode 4.

The portion of the insulator which is exposed inside of the cylinder is in the form of a tapered nose 10, and is surrounded by the 40 skirt 11 of the shell 1, so as to leave a space between the skirt and the nose of the insulator. The provision of this space and its proper shape and proportioning are important for well understood reasons, as upon the 45 proper construction of these parts depends prevention of the accumulation of carbon and oil on the nose of the insulator, which would result in fouling the plug and the establishment of a conducting path between the center electrode 4 and the skirt 11 along the surface 50 of the porcelain. The particular construction of these parts constitutes no part of the present invention, except in so far as the invention provides for incorporation of the 55 variable gap, to be hereinafter described, in such a way as not to reduce the efficiency of these parts of the plug in the performance of their proper functions.

In the construction illustrated, the means 60 forming the second and movable electrode of the spark plug comprises a bi-metallic strip 6 mounted on the lower end of the skirt 11 of the spark plug shell 1 and carrying the firing point 8, the space between 65 the tip of which and the end of the central

electrode 4 constitutes the spark gap 13. The end of the strip 6, remote from the firing point 8, is firmly attached to the spark plug shell in any suitable manner. In the particular construction illustrated, the strip is 70 formed with an ear 7 which is set in a milled recess in the lower face of the skirt 11, said ear being secured in such recess in any suitable manner, such as by crimping or compressing the metal of the skirt tightly against 75 the ear by means of a blow from a punch or by press operation. For the purpose of assuring a permanent mounting which cannot become loose in operation, the ear 7 is preferably provided with a groove 7^a in one of 80 its faces, into which the metal of the shell is deformed by pressure to prevent interlocking. Such groove 7^a is desirably straight and of sufficient length to assure stability of the bi-metallic strip. 85

The firing point 8 may be formed in any suitable manner, preferably by bending the end of the bi-metallic strip radially inward toward the central electrode, as shown, and tapering it down to an appropriate shape. 90 The strip 6 is so formed that the free portion of it, between the point of its attachment to the spark plug shell and the firing point, will warp or become deformed upon a change of temperature so as to move the firing point 95 8 toward and from the fixed firing point 4. Preferably the strip 6 is formed of two layers of metal firmly united together, the inner layer of which has a greater co-efficient of expansion than the outer layer, so that when 100 the strip becomes heated it will warp in a direction to widen the spark gap.

In the embodiment of the invention illustrated, it will be seen that the free portion of the strip 6 extends parallel to the plane 105 of the lower end of the skirt 11, that it in general follows the cylindrical curvature of the skirt so as to overlie the lower end thereof, and that one face of it is brought into close proximity to, or preferably into substantial 110 contact with the end of the skirt, such contact preferably extending throughout all or the larger part of the length of the strip. This construction embodies and illustrates very important features of my invention. 115

In the first place it is very important to have the movable firing point and its thermo-responsive supporting means so constructed and arranged as not to become heated during the operation of the engine to such a degree 120 as to cause preignition. In installations where the tendency to overheat is pronounced, overheating may be prevented by the extended contact between the strip and the end of the spark plug shell. It will be 125 understood that the spark plug shell, being screwed directly into the cylinder casting is maintained at a suitable temperature comparable to that of the casting itself which latter temperature is controlled by the water 130

jacket or other cooling means of the engine. The bi-metallic strip being mounted in close contact with the end of the spark plug shell, which contact, as stated, preferably extends 5 substantially throughout the length of the strip, readily transfers its heat to the end of the shell, and is thus sufficiently cooled to prevent preignition although not to such an extent as to prevent it from warping to open 10 the spark gap. The contact between the edge of the strip and the end of the shell should be made as extensive and as close as is convenient. The strip may be brought into such close contact with the end of the shell that 15 there is actually some pressure between them, just so long as the engagement is not sufficient to prevent the proper change in shape of the strip at different temperatures. The force available for movement of the strip, 20 due to relative expansion of the metals therein, is very considerable and can overcome considerable friction between the edge of the strip and the end of the shell.

For most efficient heat dissipation there 25 should not be enough space between the edge of the strip and the end of the shell to permit any free circulation of the gases between the two at the points where it is expected that the heat shall be transferred because such gases 30 would act as a thermal insulator and would cut down the heat transference.

While it is desirable, as stated, that the bi-metallic strip 6 be mounted for movement parallel to the lower face of the shell and in 35 actual contact therewith, precision of adjustment to secure close or continuous contact is not in fact imperative. Where the bi-metallic strip does not closely engage the shell, the accumulation of carbon on the lower 40 face of the shell will establish a heat transferring relationship and assist in maintaining the temperature of the bi-metallic strip, including the firing point 8, within the desired temperature range. This carbon deposit 45 will form and transfer heat provided the space is not so great as to permit free circulation of gases. Such circulation would prevent the formation of such a carbon deposit. The depositing of carbon on the shell 50 will not, however, result in building up a thick carbon layer between the shell and the bi-metallic strip or around the strip, for the reason that the bi-metallic strip will have wiping or scraping contact with the carbon 55 and will prevent an accumulation of the carbon beyond the thickness which may actually be required for bridging the very short space between the bi-metallic strip and the shell.

The arrangement of the strip 6 parallel to the plane of the end of the plug and with its free part overlying the end of the skirt, disposes the strip in such manner that it does not choke or interfere with the action of the space 12 between the skirt and the nose of the porcelain. It therefore has no tendency to

cause fouling or short circuiting of the plug. The location of the strip in the plane parallel to that in the end of the plug also results in a very compact construction in which there are no extended parts which might reduce 70 the cylinder clearances. The concentric arrangement of the strip 6 with reference to the end of the plug also permits the free portion of the strip to be extended to the necessary length to produce the desired amount 75 of movement under temperature change, while still maintaining the compact form. By attaching one end of the strip 6 directly to the plug shell as by means of the ear 7 fitting in the slot, and by forming the firing 80 point 8 as an integral part of the strip, all separate elements, such as pins, screws and the like which might become loose or detached are avoided.

It is further to be observed that in my construction the firing point having the thermo-responsive mounting is the point which is carried by the shell of the plug rather than the central electrode. This is important for two reasons: first, that it provides for the transference of the heat of the thermo-responsive element directly to the spark plug shell, and so to the cylinder casting, and cooling system, thus preventing such overheating of the thermo-responsive element as would result in 95 preignition; and second, that it avoids the necessity of associating any moving or adjustable parts with the porcelain. If it were attempted to associate such moving parts with the porcelain, difficulties would be encountered in preventing breakage of the porcelain or other insulating material due to such movement.

As has been stated, it is a further object of the invention to so construct the thermostatic element that carries the movable electrode that the gap will be automatically increased to its maximum width somewhat below the normal operating temperature, and will remain at such width without the necessity of 105 employing an extraneous stop so that further heating of the element does not subject the parts thereof to strain nor result in increasing the spark gap to a length greater than that desired.

In accordance with the present invention, this is accomplished by combining into a bi-metallic strip two metals or alloys which have substantially different co-efficients of expansion up to the point at which it is desired to 110 arrest distortion of the thermostatic element, but whose co-efficients of expansion become and remain substantially equal at and above such predetermined temperature.

It has been found that this result can be obtained in a very satisfactory manner by making the outer metallic strip of the thermostatic element of invar which is a nickel steel alloy having approximately thirty-six per cent (36%) nickel and sixty-four per cent 125 130

(64%) steel and the inner metallic strip of the thermostatic element of an alloy having substantially the following composition:

Carbon	.50
Manganese	.70
Silicon	.75
Chromium	8.00
Nickel	22.00
Copper	2.00
10 Cobalt	1.00
Iron	64.05

As is well known, invar has an almost negligible co-efficient of expansion from 0° C. 15 to approximately 100° C., but the co-efficient of expansion increases rapidly from 100° C. to approximately 300° C. Above the latter temperature the co-efficient of expansion of invar becomes substantially uniform but is 20 quite substantial, being approximately equal to the co-efficient of expansion of the alloy of which the other strip of the thermostatic element is constructed. Said other strip has a substantially uniform co-efficient of expansion 25 both below and above 300° C., and in fact throughout substantially the entire operating range of temperatures to which it is subjected in use.

With the thermostatic element constructed 30 as described, it will be apparent that the thermostatic element will attain its maximum distortion at the temperature at which the co-efficients of expansion of the two metallic strips become substantially equal; that is to 35 say, at about 300° C.

With the construction as shown and described herein, the minimum spark plug gap is adjusted to fifteen thousandths of an inch, and, upon heating, the thermostatic element 40 automatically increases the gap to approximately thirty-four thousandths of an inch and then causes the gap to maintain this width irrespective of further heating until the thermostatic element is again cooled below the 45 temperature at which such maximum length of the gap is ordinarily reached.

For the purpose of providing a thickness gauge to enable the gap to be measured when the parts are cooled, provision is made of 50 a washer 9 which is normally held in place upon the upper end of the spark plug by the terminal binding nut 5. When it is desired to test the width of the gap, the washer 9 may be removed from the spark plug and an ear 55 14 on the washer, of predetermined thickness, may be used as a thickness gauge. If desired the thickness of this ear may be marked directly thereon.

The spark plug illustrated in Figures 5 to 7 60 is the same as the spark plug already described, with the exception that the means for attaching the bi-metallic strip to the shell is modified.

In this form of the invention the bi-metallic strip 6 is provided with pins 15 which may be

non-circular in cross section. Round holes 16 are drilled in the lower end of the shell 1 for the reception of these pins. The non-circular pins 15 are driven into the round holes, the relative dimensions of the pins and holes being such that the pins are deformed by such driving into a shape to fit the holes. This effects a very firm securement of the bi-metallic strip to the shell. For the purpose of further strengthening the connection, a 70 punch or press may be subsequently applied to exert pressure transversely of the pins through the lower end of the shell at that portion which receives the pins. The area of application of such pressure is indicated, for 75 example, by the depressed portion 17 of Figure 5.

While I have illustrated and described in detail a preferred form of my invention, it is to be understood that changes may be made 80 therein and the invention embodied in other structures. I do not, therefore, desire to limit myself to the specific construction illustrated, but intend to cover my invention broadly in whatever form its principle may be utilized.

I claim:

1. In a spark plug, in combination, a metallic shell adapted to be located in intimate, heat transferring relation with the cooling 95 system of the motor, a fixed central electrode insulated from said shell, a movable electrode cooperating with the fixed electrode, and a thermostatic element controlling the movable electrode, said thermostatic element being mounted on the shell and being disposed throughout substantially its entire length in efficient heat transferring relation to the shell.

2. In a spark plug, in combination, a metallic shell adapted to be located in intimate, heat transferring relation with the cooling system of the motor, a fixed central electrode insulated from said shell, a movable electrode cooperating with the fixed electrode, and a thermostatic element controlling the movable electrode, said thermostatic element being mounted on said shell and projecting below the lower face thereof, and being arranged to make wiping contact throughout substantially its entire length with the lower face of the shell.

3. In a spark plug, in combination, a metallic shell adapted to be located in intimate, heat transferring relation with the cooling system of the motor, a fixed central electrode insulated from said shell, a movable electrode cooperating with the fixed electrode, and a thermostatic element controlling the movable electrode, said element being mounted on the shell and movable substantially parallel to the lower face of the shell and in proximity throughout substantially its entire length, to said lower face of the shell.

4. In a spark plug, in combination, a metallic shell adapted to be located in intimate,

- heat transferring relation with the cooling system of the motor, a fixed central electrode insulated from said shell, a movable electrode cooperating with the fixed electrode, and a 5 bi-metallic strip integral with the movable electrode and intimately united with the shell, said element being movable parallel to the lower face of the shell and in close proximity thereto.
- 10 5. In a spark plug, the combination of a shell, an insulator, an electrode mounted in said insulator and a bi-metallic strip attached at one end to the end of said shell and carrying a movable firing point, said bi-metallic strip moving in a plane parallel to the plane 15 of the end of said shell.
6. In a spark plug, in combination, a metallic shell adapted to be located in intimate heat transferring relation with the cooling system 20 of the motor, a fixed central electrode insulated from said shell, a movable electrode cooperating with the fixed electrode, and a bi-metallic element mounted on said shell and extending parallel to the lower face of the shell, said element being distortable by 25 temperature changes and arranged when so distorted to produce movement of the movable electrode in a direction substantially parallel to the lower face of the shell.
- 30 7. In a spark plug, in combination, a metallic shell adapted to be located in intimate heat transferring relation with the cooling system of the motor, a fixed central electrode insulated from said shell, a movable electrode co- 35 operating with the fixed electrode, and an arcuate, bi-metallic element carrying the movable electrode, said bi-metallic element being mounted on the shell and substantially concentrically disposed with relation thereto.
- 40 8. In a spark plug, the combination with a central, fixed sparking electrode, of an insulator carrying said electrode, a metallic shell having a skirt portion so spaced from the insulator that an insulating and carbon 45 scavenging space is provided between the skirt and the insulator, said skirt portion of the metallic shell being threaded for secure- 50 ment in intimate, heat transferring relationship to the cooling system of a motor, a second movable electrode cooperative with the fixed electrode to form a sparking gap, and a bi-metallic strip mounted in the lower end of the shell and carrying the movable electrode, said bi-metallic strip being mounted 55 edgewise upon the lower face of the skirt portion so that obstruction of the scavenging space by it is substantially avoided.
9. In a spark plug, in combination, a metallic shell adapted to be located in intimate, 60 heat transferring relation with the cooling system of the motor, a fixed central electrode insulated from said shell, a movable electrode cooperating with the fixed electrode, and a bi-metallic strip mounted on the shell and carrying 65 the movable electrode, said bi-metallic strip being provided with an ear set into a recess in the shell, and said ear being provided with a groove into which the metal of the shell is pressed.
10. The method of making a spark plug, 70 comprising a metallic shell and an electrode carrying bi-metallic strip mounted thereon, which comprises providing a shell having a recess in the lower end thereof, providing a bi-metallic strip having an ear adapted to be 75 inserted in said recess, which ear is provided with a depression in one face thereof, inserting the ear in the recess of the shell and compressing the shell transversely of said ear to press the metal of the shell into said recess. 80
11. In a spark plug, the combination with a fixed sparking electrode, of a second sparking electrode movable to change the length of the spark gap, and a thermostatic element controlling the movement of said second electrode in accordance with temperature conditions, comprising two metallic strips having different co-efficients of expansion up to a certain temperature, and substantially equal co-efficients of expansion above such temperature. 85
12. In a spark plug, the combination with a fixed sparking electrode, of a second sparking electrode movable to change the length of the spark gap, and a thermostatic element controlling the movement of said second electrode in accordance with temperature conditions, said thermostatic element being characterized by the fact that it is distortable by 90 temperature changes up to a certain temperature, and is inherently substantially non-distortable above such temperature.
13. In a spark plug the combination with a fixed electrode of a second electrode composed of two metallic strips having different co-efficients of expansion up to a certain temperature, and substantially equal co-efficients of expansion above such temperature. 95
14. In a spark plug the combination with a fixed electrode of a second electrode composed of two metallic strips having different co-efficients of expansion throughout a pre-determined temperature range, and substantially equal co-efficients of expansion throughout another predetermined temperature range. 100
15. In a spark plug, a shell adapted for securedment to a motor cylinder, a fixed sparking terminal, a second sparking terminal cooperative with the first, and a bi-metallic strip 110 mounted on said shell outside the inner boundary of the lower end thereof in substantial parallelism with the lower end thereof and supporting the second sparking terminal, said strip being arranged to flex in a plane 120 substantially perpendicular to the axis of the shell in response to temperature changes and thereby to separate the sparking terminals as the temperature rises. 125
16. In a spark plug, a fixed central spark- 130

ing terminal, an arcuate, bi-metallic strip secured at one end to a marginal portion of the spark plug and extending edgewise around the central sparking terminal in a 5 plane substantially normal to the axis of the spark plug, and a second sparking terminal carried at the free end of said strip, said

strip being constructed to expand as the temperature rises, and so to carry the terminal mounted on it away from the fixed terminal. ¹⁰

In testimony whereof I have affixed my signature to this specification.

HERMAN SCHLAICH.
